UNITED STATES PATENT OFFICE.

GEORGE B. KOHLER, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

FARE-BOX.

1,058,602.

Specification of Letters Patent.

Patented Apr. 8, 1913.

Application filed February 14, 1910. Serial No. 543,707.

To all whom it may concern.

Be it known that I, GEORGE B. KOHLER, a citizen of the United States, residing in Philadelphia, Pennsylvania, have invented 5 certain Improvements in Fare-Boxes, of which the following is a specification.

My invention relates particularly to fare boxes used in passenger cars or station platforms for the collection of fares as the passenger enters the car, but it will be understood that the box may be used for other purposes without departing from my invention.

The main object of my invention is to so 15 construct the fare box that it cannot be tampered with.

A further object is to provide means for closing the box when the fare receptacle is removed and to close the fare receptacle as 20 it is withdrawn from the box.

My invention further relates to improvements in construction whereby more than one conductor can use the box without the necessity of discharging the contents of the 25 fare receptacle every time a conductor takes a car after the first run, and to provide against using the box when the fare receptacle is not in place.

In the accompanying drawings:—Figure 30 1, is a perspective view of the improved fare box, showing the drawer carrying the fare receptacle in position to be inserted in the box; Fig. 2, is a sectional elevation of the improved fare box showing the platform of 35 the fare receiving section in the closed position; Fig. 3, is a view of a portion of Fig. 2 enlarged, showing the platform of the fare receiving section in the discharging position; Fig. 4, is an enlarged sectional 40 plan view on the line 4—4, Fig. 2; Fig. 5, is an enlarged sectional plan view on the line 5—5, Fig. 2; Fig. 6, is a perspective view of the hopper section of the box; Fig. 7, is a perspective view of the pivoted frame; Fig. 45 8, is a perspective view of a portion of the rear of the drawer; Fig. 9, is a perspective view of the locking lever for the pivoted frame; Fig. 10, is a rear view of the toothed wheel shown in Fig. 7; Fig. 11, is a sectional view of part of Fig. 2, enlarged; and 50 Figs. 12, 13 and 14, are sectional views on the line 12—12, Fig. 4, showing the parts in different positions.

A is the body of the box, made as shown 55 in Fig. 1, having a drawer B at the lower

end for the fare receptacle C. Mounted on the upper end of the box is a fare receiving section D preferably made of metal, the frame d having glazed sides and inclined deflectors d'. The frame is open at the top 60 and the edge is preferably beveled, with raised rounded portions at the corners to prevent the retention of fares at the upper end of the receiving section.

The base d² of the fare receiving section 65 has an opening communicating with the interior of the box, and within the box directly under this opening is a hopper a which communicates with a pivoted chute E. The chute is mounted on pivot pins e which 70 have their bearings in the body of the box, and one of the pivot pins extends outside the box and is provided with a handle e' by which the chute is shifted from one position to another.

e² is an indicator arm which strikes 75 against projecting pins e³ mounted in a casting in the box, and the chute can be shifted from one position to another by pressing first one pin and then another. The object 80 of this construction is to prevent accidental shifting of the chute to a greater distance than one compartment of the receptacle at a time, as the chute cannot be returned after it is moved forward until the fare receptacle 85 is removed.

In order to close the opening in the base 90 d² of the fare receiving section I provide a plate f which is pivoted to a segmental carrier F mounted on a pivoted shaft F' having its bearings in the hopper a. The plate is also connected to a pivot pin t by a link f' so that when the shaft F' is turned from the position illustrated in Fig. 1, to that shown in Fig. 3, the plate will quickly discharge 95 the fare into the hopper.

F² is the operating handle for the discharge mechanism, pivoted at f² to the case and connected by a link f³ to an arm f⁴ on the shaft F'. The handle is also connected 100 to the long arm of a lever G pivoted to the case; the short arm of said lever being connected by a link g to a bolt G' mounted in the frame and engaging the drawer, as clearly illustrated in Figs. 2 and 12, so as 105 to prevent the opening of the drawer until the handle is moved in a position to discharge any fare which is in the fare receiving section.

A' is a partition separating the body of 110

the box from the drawer compartment, mounted on which is a hopper section H having beveled partitions h. The spaces between these partitions are open and aline with openings in the partition A', and these openings in turn aline with openings c in the fare receptacle C.

J is a sliding plate valve for closing the openings in the hopper H; this valve is located between the hopper frame and the partition A' and has a depending lug j which is in the path of the drawer B. Springs j', Fig. 5, are attached to the valve J and the partition and tend to close the valve as soon as the drawer is opened, but when the drawer is pushed in to its full extent it strikes the lug j and opens the valve, so that its openings aline with those of the hopper H and partition A'.

20 Mounted in the drawer B is the fare receptacle C. This receptacle can be removed bodily from the drawer and another receptacle placed therein.

C' is the sliding cover of the receptacle, having a series of openings alining with the openings in the receptacle, four in the present instance, held in the closed position by a spring lock c' and closed when the drawer is pulled out by a projecting pin c² striking 25 a tooth of a wheel I' described hereafter.

30 In the fare receptacle is a series of independent containers C² which receive the fares which pass through the several openings, as shown in Fig. 2. These containers can be removed when the proper official 35 opens the fare receptacle and the fares in the several containers counted separately. The toothed wheel I' is carried by a pivoted frame I, Fig. 7. This frame has a pivot rod i which has its bearings in the hopper H and at the forward end of the frame is a shaft i' on which the toothed wheel I' is loosely 40 mounted. On this wheel are pawls i² which engage a ratchet wheel i³ secured to said shaft, so that the wheel I' is free to turn only in one direction. On the rear end of the frame I are depending lugs i⁵ which extend through openings in the partition A' and rest on the fare receptacle in the drawer.

45 50 B, when the drawer is opened the frame is tilted and the lugs drop back of the drawer, raising the wheel which releases the lug c² of the slide cover C'. In the meantime the sliding cover C' has been closed and locked; 55 the slides B' at each side of the drawer allow it to be drawn out the full distance but it cannot be detached from the casing of the box. The receptacle is removed from the drawer and unlocked by the proper official.

60 A locking dog s is pivoted to the case and has one arm which extends into the path of the fare receptacle; another arm is connected to a spring s³ attached to the case.

65 The dog is notched to form a hook s' which engages a pin i⁶ on the frame I, so that

when the receptacle is withdrawn from the case the frame I tilts and the dog s being released engages the pin i⁶ on the frame I and retains the frame until released on the reinsertion of the receptacle.

70

When the drawer is closed without the fare receptacle, it clears the arm of the dog s and strikes against the lugs i⁵ which cannot be raised owing to their being locked by the dog s, but when the fare receptacle is in place in the drawer and the drawer closed the receptacle comes in contact with the dog, releasing the frame I and allowing the drawer to tilt it as it strikes the lug and pass under to the closed position, when it is fastened by the lock b'. The bolt G' will also engage the back of the drawer, so that it cannot be opened without first operating the lever F².

75

80 Mounted in an extension i⁴ of the frame I is a spring bolt i⁵, which is beveled on one side, and engages a toothed segment e⁴ on the pivoted chute E, so that when the chute is shifted from one position to another it is prevented from returning until the drawer 85 is opened. A weight E' on the chute tends to hold the teeth of the segment against the bolt, as shown in Fig. 2, and to restore the chute to its initial position upon the opening 90 of the drawer.

95

95 At one portion of the fare box I provide a compartment N having a door n; the front end of the box is slotted at n' and this slot communicates with the interior of the compartment N. This compartment is intended 100 for tickets and memorandum slips which are not to be entered as paid fares.

100

105 By the above construction it will be seen that I am enabled to make a fare box especially applicable for passenger cars, in which the passenger pays the fare on entering the car and in which the fares need not be collected from the box except at the end of the day's run, as the fares of each conductor making the trips are collected in separate compartments and the fares are kept 110 separate even after the fare receptacle is removed from the box and until they are finally counted.

110

115 If any attempt was made to use the fare box without the fare receptacle the openings in the partition would be closed and the fares inserted in the box would simply accumulate above the partition and would only be discharged into a fare box when in proper position in the drawer, and the drawer could not be closed until the fare receptacle was in position.

125

120 Means are provided which will prevent the insertion of any tool to actuate the locking mechanism, and mechanism is also provided to prevent the removal of the drawer or fare receptacle without first discharging the contents of the receiving section of the fare box.

130

I claim:—

1. The combination in a fare box, of a body portion, a transverse partition therein having an opening for the passage of fares, 5 a detachable fare receptacle under the partition and having an opening therein alining with the opening in the partition, a sliding cover for the fare receptacle, means for locking the sliding cover when in the closed position, a pivoted frame located at the partition, a shaft on said frame, a toothed wheel on the shaft, a pawl and ratchet mechanism between the toothed wheel and its shaft so as to prevent the wheel turning in one direction, but allowing it to freely turn in the opposite direction, a pin on the sliding cover adapted to engage the teeth of the said wheel, and projections on the rear end of the frame resting on the fare receptacle, so that 15 on the first movement of the receptacle the lid is closed and locked and then the wheel is released to allow for the withdrawal of the fare receptacle with the projecting pin.
2. The combination in a fare box, of a body portion, a fare receptacle therein having a series of openings and a series of compartments, means for closing said openings, an adjustable chute for directing the fares to any one of the openings, a frame pivot-

ally mounted in the body portion having a 30 device for actuating the closing means of the fare receptacle, a spring bolt carried by said frame, and a toothed segment on the chute with which the spring bolt engages.

3. The combination in a fare box, of a drawer arranged to slide in an opening in the fare box, a receptacle therein having a sliding cover, a pin projecting from said cover, a pivoted frame mounted in the fare box, a ratchet wheel carried by said frame 40 and arranged in the path of the pin, the rear end of the frame having downwardly projecting portions in the path of the drawer and fare receptacle, and a locking dog pivoted to the body of the fare box and 45 arranged to engage the frame and located in the path of the fare receptacle, the frame preventing the closing of the drawer unless it is released by the receptacle mounted in the drawer acting upon the dog. 50

In testimony whereof, I have signed my name to this specification, in the presence of two subscribing witnesses.

GEORGE B. KOHLER.
